NEEDLE GRINDER

Fred Crossman and Earl A. Southam, Cleveland,
and George J. Ruhl, Shaker Heights, Ohio, as-
signors to The Lindsay Wire Weaving Com-
pany, Cleveland, Ohio, a corporation of Ohio

Application January 29, 1945, Serial No. 575,047

5 Claims. (Cl. 51—241)

1

This invention relates to apparatus for grinding the points on needles used in diamond die drilling machines. The needles are intended to drill holes varying from four ten-thousandths of an inch to five thousandths of an inch in diameter.

One of the difficulties encountered in drilling fine holes in diamonds has been the necessity for maintaining a sharp point on the needles, and at the same time maintaining the desired angle of taper at the work engaging end thereof. It is important, however, to maintain the desired angle of taper in order to assure the desired shape of bore in the diamond die. Heretofore the practice has been to remove the needle frequently from the machine, transport it to a grinding machine, dress the point and replace it in the drilling machine. This was not only a time consuming operation, but was objectionable in that there was danger in bending the point by frequent removal and replacement of the needle. The points of such needles are so fine that if one be struck against any part of the machine the point may thus be bent and thereby rendered useless without another grinding operation.

An object of the present invention is to construct a grinding or dressing apparatus which will enable the point of a needle to be dressed while it remains in the machine. In addition, the invention contemplates a construction wherein the angle of taper to be ground on the point of the needle may be accurately controlled by the operator, and wherein the pressure applied on the grinding member against the needle may likewise be under control of the operator.

We have shown our invention in connection with a diamond die drilling machine wherein Fig. 1 shows the front view of the machine; Fig. 2 is a top plan view thereof; Fig. 3 is an end view of the machine; Fig. 4 is a section taken on the line 4—4 of Fig. 3; Fig. 5 is a section taken on the line 5—5 in Fig. 2; Fig. 6 is a section taken on the line 6—6 in Fig. 4; and Fig. 7 is a view showing the work table having a diamond die mounted in its holder and supported on the table.

The diamond die drilling machines which we have illustrated in our drawings has a frame which includes spaced horizontal plates 10, 11 and 12. A work table 13 is disposed above the

2

plate 11 and supports a diamond die holder 14. Such holder is specially built to hold a diamond die indicated at 15, Fig. 7, and is provided with flared portions 16 and 17 on opposite sides of the diamond for facilitating handling of the wire to be drawn therethrough after the opening has been drilled therein. The work table may be mounted upon a spindle 18 which is journaled in the plates 11 and 12 and which is adapted to be rotated from a source of power (not shown) by a belt 19 which extends around a pulley 20 on the spindle 18.

The needle which is adapted to drill a hole in the diamond 15 is indicated at 25 as being carried by and depending from a holder 26 which is in the form of a spindle and extends above and below a driving mechanism indicated in general at 27. The drive mechanism may be rotated by means of a belt 28 which is connected to any suitable source of power, such as an electric motor, not shown.

During the die drilling operation the needle is adapted to be intermittently raised and lowered and for such purpose the spindle is shown as having a collar 29 which provides a shoulder against which the forked end of the lever 30 may engage, the lifting being accomplished by the tilting of the lever about the pivot 31. The tilting action may be effected by means of spaced cams 32 on a wheel 33 which is journaled on a shaft 34 and is adapted to be rotated by a belt 35 from any suitable source of power. The shaft 34 may be journaled in brackets 36 which are attached to a plate 37. The last-named plate is rigid with the housing for the drive mechanism 27 which in turn may be affixed by a plate 38 to the frame plate 10.

The needle dressing mechanism embodying the present invention includes an abrasive member 40 shown in the form of a disc or wheel which is affixed to a shaft 41 that is journaled in bearings 42 and 43. The shaft and abrasive member are so supported that the member may be adjusted vertically with respect to the needle, and may also be adjusted angularly with respect to the needle, and may be moved toward and away from the needle under pressure exerted by the operator. The angular adjustment of the grinding member controls the taper to be imparted to the end of

the needle and may be accomplished by pivoting the shaft 41 at a point intermediate its ends. Thus, in Fig. 6, the pivot is shown as a pair of pointed thumb screws 45 which are carried by arms 46 which extend from and are rigidly attached to a cross bar 47. The bar 47 also has rigidly fastened thereto a pair of depending arms 48 which are slotted at 49 to receive pins 50 that project laterally from the bearing 43 and operate to support the bearing for vertical movement with reference to the arms 48. The vertical movement may be controlled by means of a thumb screw 51 which is in threaded engagement with the bar 47 and which is adapted to engage the upper surface of the bearing 43. A spring 52 bears against the under-surface of the bearing and also against a tie plate 53 which connects the lower ends of the arms 48. Thus, by adjusting the screw 51, the shaft 41 is caused to swing about the pivot 45 and thereby to vary the angle of the abrasive member 40 with relation to the needle.

It is desirable to so mount the abrasive member 40 that it may be moved toward and from the needle while the grinding face thereof is maintained parallel to its original position. This we accomplished by pivotally supporting the cross bar 47 upon parallel links 55 and 56 by studs 57 and 58. The other ends of the links are pivotally connected at 59 and 60 to a cross bar 61 that is adapted to be adjusted vertically with respect to the frame plate 10. The means for obtaining the vertical adjustment of the cross bar 61, and thereby obtaining vertical adjustment of the shaft 41 and its associated grinding member 40, preferably comprises an adjusting screw 65 which is adapted to extend through a threaded opening in a cross bar 66 and to engage at its lower end the upper surface of the cross bar 61. The bar 66 is rigidly held with respect to the members 59 and 60 by nuts 67 and the bar 61 is held in engagement with the lower end of the thumb screw 65 by springs 68 which surround the members 59 and 60 respectively and are disposed between the links 55 and 56 and the plate 10.

To limit the movement of the grinding member toward and from the needle, we have shown a stop device in the form of a thumb screw 70 which is in threaded engagement with a passage-way in a block 71 and which may be affixed to the arm 46 as shown in Figs. 1 and 6. The leading end of the thumb screw is adapted to engage a part of the frame which in Fig. 1 is illustrated as an angle plate 72 and is fastened to the underside of the plate 38. Thus, by adjusting the axial position of the screw with reference to the block 71, the movement of the grinding member toward the needle may be accurately limited so as to control effectively the extent to which the needle will be ground.

In using the grinding device embodied in the present invention, we prefer to adjust the position of the lever 30 by turning the thumb screw 75 which controls the vertical position of the pivot 31 so as to have a clearance between the forked end of the lever 30 and the collar 29. At such time the needle is supported by the driving mechanism which is operated to effect rotation of the needle but without imparting an intermittent or reciprocating motion thereto. It is to be understood that the needle is first lifted and that the diamond die is removed from the work table 13 and that the needle is then allowed to drop to its normal position as shown in Fig. 1.

The grinding member is then adjusted vertically by proper manipulation of the thumb screw 65 and is adjusted angularly by manipulation of the set screw 51. Thereupon the grinding member 40 is rotated under the influence of the driving belt 76 which extends around the pulley 77 that is affixed to the shaft 41 and the grinding member together with its associated supporting mechanism is moved as a unit towards the needle until the forward movement thereof is arrested by the stop mechanism 70 and 72. By carefully adjusting the set screws 65, 51 and 70, the pressure exerted against the needle can be accurately controlled, and the angle of grind can likewise be adequately varied to suit the particular requirement of the work required to be performed by the needle. The forward and backward movement of the dressing member may be accomplished by light finger pressure against any part of the shaft supporting mechanism.

We have found that our invention not only has obviated the necessity for frequent removal of the needle from the drilling machine for dressing purposes, but that the time required for the grinding operation has been greatly reduced, and that the shape of the needle can be accurately controlled to an extremely fine degree.

We claim:

1. A device of the character described, comprising a grinding member, a shaft therefor, means for pivotally mounting the shaft while permitting rotation thereof so as to vary the angle of the grinding member with respect to the work, other means including parallel links for supporting the first-mentioned means to effect a movement of the grinding member toward and from the work, and second-named means including a device for shifting the first-mentioned means and the grinding member as a unit with reference to the work.

2. In a device of the character described, the combination of a frame, a bar mounted for movement toward and from the frame, a pair of links pivotally connected to the bar adjacent one end of the links, a second bar pivotally connected to the links adjacent the other end thereof, a grinding member, a driving shaft therefor, and means carried by the second bar for journaling the shaft and for supporting it for pivotal movement with respect to the second bar.

3. In a device for grinding a drill in a drill-spindle in operative position relative to a work table, the combination of a support adapted to be adjustably positioned at the side of the space between the drill spindle and table, a pair of links pivotally connected at one end to said adjustable support, a member pivoted to the other ends of said links, a bearing pivotally carried by said member, a shaft journaled in said bearing, grinding wheel operated by said shaft and adapted to engage a drill in the spindle, and means for tipping said shaft and holding it in selected position to present the grinding wheel at the desired angle to the drill.

4. The combination with a diamond die drilling machine having means for supporting and rotating the needle and a table aligned therewith of a grinding device comprising a grinding member mounted for rotation and disposed at one side of the needle between the shank of the needle and the table, means for supporting the grinding member for movement toward and from the needle generally in a direction transversely of the axis of the needle, said supporting means includ-

ing a device for adjusting the grinding member axially of the needle and angularly with respect to the needle, and means for limiting movement of the member toward the needle.

5. A device of the character described comprising in combination, a frame, a grinding member, a carrier therefor, an adjusting member resiliently supported on the frame, means for supporting the carrier on said adjusting member and adapted to permit movement of the grinding member transversely toward the work, an adjusting screw engaging said adjusting member and operating to move it against the force of its resilient support so as to vary the position of the grinding member axially of the work, a shaft on the carrier for rotating the grinding member, and

10

other means for varying the angle of the grinding member with respect to the work.
